UNITED STATES PATENT OFFICE

2,112,281

GRIP FOR MANILA ROPE AND THE LIKE

Robert G. Ferris, Harvard, Ill., assignor to Starline Inc., Harvard, Ill., a corporation of Illinois

Application May 2, 1936, Serial No. 77,647

6 Claims. (Cl. 24—123)

This is an improvement in rope grips, particularly those on hay carriers like that shown in Ferris Patent No. 1,759,549, granted May 20, 1930, wherein there is a short section of steel rope or cable connected at one end to the carrier, and at the other to the manila or other fiber rope.

An object of this invention is to provide a connection between the steel cable and the manila rope which is flexible so as to pass readily around the sheaves of the carrier and which firmly grips the fiber rope without injury thereto.

This and other objects, as will hereinafter appear, are accomplished by this invention which is fully described in the following specification and shown in the accompanying drawing, in which—

Figure 1 is a side elevation of the end of a manila rope having the rope grip of this invention applied thereto;

Fig. 2 is an enlarged elevation of the rope grip removed;

Fig. 3 is an enlarged section on the line 3—3 of Fig. 1;

Fig. 4 is a view similar to Fig. 2 showing a modified form of the rope grip;

Fig. 5 is a view similar to Fig. 4 showing the end of still another modified form of anchoring device for the rope grip;

Fig. 6 is a view similar to Fig. 3 showing another form of anchor;

Fig. 7 is a view similar to Fig. 1 showing a modified form of grip connecting two abutting rope ends; and

Fig. 8 is still another modified form of rope grip.

The embodiment shown in Figs. 1, 2 and 3 comprises a rope grip A applied to a manila rope B. The rope grip consisting of a flexible braided tubular structure, as shown in Fig. 2, consists of strands 10 each made up of a number of wires twisted together to form a rope of steel, brass, or the like interwoven with similar ropes 11 running in the opposite direction. These ropes having their beginning at the bottom of Fig. 2 pass up and are braided, as shown, or bent to form the loop 12, and on their return are interwoven with the opposite ends of the strands and terminate at the bottom of Fig. 2.

One of the strands 10 is then twisted with one of the strands 11 at the bottom to form a "pig tail" 13 which preferably has an enlarged end 14, which in this case may be a drop of solder.

To assist in keeping the strands of the loop 12 together they may be soldered at 15, or they may 55 be held by means of a band which is passed

around the several strands and secured thereto as by means of solder.

In use the free end 13 of the manila rope may be passed upwardly through the tubular grip which is enlarged by pressing the ends toward each other after the manila rope has been carried well up toward the loop 12, the rope grip is pulled down so as to press it firmly against the manila rope. When the lower end of the rope grip is reached, the pig tails 13 may be forced through between the strands forming the rope as shown in Fig. 1. The hold which the strands of the rope thus have upon these pig tails is not relatively very great, but it is sufficient to hold these pig tails thereby "snubbing" them, so that when a strong pull comes on the loop 12 the flexible grip will close in about the manila rope so as to firmly grip the same.

To the loop 12 is secured a steel rope or cable 47, corresponding to the cable 47 of the patent, having an eye 48 connected directly to the loop or (as shown) by means of a link 49. This grip has proved to be very satisfactory in use. By carrying the fiber rope well up into the loop 12 the loop has no tendency to twist in use which is very necessary to prevent breakage of the strands forming the loop.

In Fig. 4 the strands of wire rope 16 start at the loop 17, run diagonally to the bottom of the grip and in returning at 16^a in the reverse direction are interwoven with or braided into the opposite ends so as to form a similar grip, the ends 18 of the strands overlapping the ends 17 and being secured thereto as by means of solder 19. Pieces of wire or wire rope 20 are then 35 looped through the lower ends of this rope grip and are twisted to form pig tails which, if desired, may have solder beads 21 at the lower ends to better enable the strands of manila rope to hold these pig tails in the same way as has been 40 shown in Fig. 1.

In Fig. 5 is shown still another modified form of anchor consisting of a flexible member 22 made of wire or wire rope with its ends secured to the lower ends of a braided wire grip which may 45 otherwise be the same as that shown in Fig. 4.

In Fig. 6 is still another modified form of anchor consisting of a staple 23 which passes through the lower end of the braided tubular portion of a wire grip like that of Fig. 4, and having ends 23^a which are bent back to firmly 50 lock the lower end of the tubular rope grip to the manila rope.

In Fig. 7 is shown a modified form of the grip 55

for securing together two abutting ends of manila ropes C and D. In this case the grip E is similar to the grip A except that its two ends are like the lower end of the grip A and each is provided with pig tails 48^a or the like for insertion between strands of the manila ropes in the way as is shown in Fig. 1. It will be understood, however, that any of the other forms of anchoring devices shown and described may be used.

10 While this grip is shown as applied to the end of a rope, it may be used intermediate the ends of the rope, as shown in Fig. 8. In this form the grip F has pig tails 48^b extending through the film rope G as before, while the opposite end of 15 the grip F terminates in a ring H of rubber or the like having a core H' of fabric, metal rope or the like about which the metal cables or ropes F forming the grip are passed at their middle, after which the ends are wound in opposite directions about a common axis and braided, the ends then being wound together in pairs to 20 form pig tails as in Fig. 2. It will be obvious that other variations of this form may be made.

The ring G can then be gripped in the same 25 way as the cable eye 48 of Ferris Patent No. 1,759,549 referred to above, the portion G' of the fiber rope extending to the left beyond the grip being attached directly to the hay carrier so as to pass through the hay carrier and to replace the 30 metal cable 47. This provides a much simpler hay carrier construction than that shown in the above patent.

Any of these grips may readily be removed by unloosing the anchoring means from the rope 35 and sliding the braided grip along the manila rope toward its end, thereby causing the grip to expand when it will readily slide off.

Thus it will be seen that a very simple and 40 efficient form of rope grip is provided and one which is flexible and adapts itself readily to the manila rope so that the latter can be bent around a sheave.

I claim:

45 1. In combination, a fiber rope, a grip for fiber rope comprising a loose tubular braid composed of interwoven strands of metal rope adapted to enclose a portion of the fiber rope, the ends of certain of the strands being secured together in pairs and being of sufficient length to enable them to pass between strands of the fiber rope to anchor the end of the grip thereto, the ends of

the inserted strands being enlarged to prevent their withdrawal through the rope.

2. A grip for securing together two abutting ends of fiber rope comprising a loose tubular braid composed of interwoven strands of metal rope in the form of a collapsible cylinder adapted to enclose the ends of the ropes, the ends of the strands being secured together in pairs and of a length sufficient to enable them to pass between strands of the fiber rope to anchor the ends of the grip thereto so that an endwise pull will cause the grip to firmly hug the rope ends. 10

3. In combination, a fiber rope, a grip for fiber rope comprising a loose tubular braid composed of interwoven strands of metal rope for enclosing the end of the fiber rope, the ends of certain of the strands being secured together in pairs and of a length sufficient to enable them to pass between strands of the fiber rope to anchor the end of the grip thereto, the opposite 20 ends of the grip forming a loop for enclosing the end of the fiber rope, the loop being short and the end of the rope extending well up into the loop so as to hold the sides of the loop apart and prevent them from twisting about each other as 25 the pull on the rope tends to cause it to unlay.

4. A grip for fiber rope comprising a loose tubular braid composed of interwoven strands of metal rope for enclosing the end of a fiber rope, the ends of the strands being secured together 30 in pairs of a length sufficient to enable them to be inserted between strands of the fiber rope to anchor the end of the grip thereto, and a ring adapted to surround the fiber rope and to slide thereover, said ring being secured to the opposite end of the strands of the rope grip. 35

5. In combination, a fiber rope, a tubular braid composed of interwoven strands of metal rope enclosing one end of a fiber rope, the inner end of the grip having pigtails passing between the strands of the fiber rope and engaging the same for anchoring the end of the grip enclosing the fiber rope to the same. 40

6. In combination, a fiber rope, a grip for fiber rope comprising a loose tubular braid composed of interwoven strands of metal rope in the form of a hollow cylinder for enclosing a portion of the fiber rope, and depending portions of the grip passing between the strands of the fiber rope for anchoring the end of the grip enclosing the fiber rope to the same. 45

ROBERT G. FERRIS.
